UNITED STATES PATENT OFFICE.

ALEXANDER SHIELDS, OF WINNIPEG, CANADA, ASSIGNOR TO CHARLES BRYDGES, OF WINNIPEG, MANITOBA, CANADA.

SANDER.

SPECIFICATION forming part of Letters Patent No. 772,436, dated October 18, 1904.

Application filed June 24, 1904. Serial No. 214,033. (No model.)

To all whom it may concern:

Be it known that I, ALEXANDER SHIELDS, a subject of the King of Great Britain and Ireland, residing at Winnipeg, Manitoba, Canada, have invented certain Improvements in Sanders, of which the following is a specification.

My invention relates to improvements in sanders for tramway, railroad, and like cars of the type which is under the control of the engineer or motorman; and it includes pneumatic means whereby the engineer may readily clean out the air-orifice which controls the supply of air to the supply of sand to force the same to the tracks.

My invention consists in the features and combination and arrangement of parts hereinafter described, and particularly pointed out in the claim.

20 In the accompanying drawings, Figure 1 represents a sectional view through the invention; Fig. 2, a plan view of Fig. 1, and Fig. 3 is a plan view showing the engineer's valve with connections leading therefrom.

25 In the drawings, A indicates a pipe which leads from the supply of sand contained in the box suitably located on the engine or car. At the lower end of this pipe a casting A is attached by a screw-thread connection at a, and a pipe B is also screw-threaded into this casting and extends therefrom at right angles to the pipe A. This pipe B forms the delivery-pipe for the sand and leads to a point in front of the driving-wheels and close to the

30 rails, with its end at such an angle that when the sand is blown through this pipe it will be deposited on the rail immediately in front of the point of contact between the wheel and the rail.

35 In order to force the sand which falls through the pipe A into the casting out through the pipe B, a nozzle C is screw-threaded into the casting A', the opening in the said nozzle having its axis coinciding with the axial line of the pipe B, so that the jet of air issuing from this nozzle will force the sand from the casting, so as to be delivered through the pipe B to the desired point.

40 It will be noticed that the nozzle is located at the rear of the casting, so that the sand is free to fall down from the pipe A in front of the nozzle without obstruction. The nozzle

45 C is combined with a cylinder or chamber C', and in this a piston D is adapted to slide back and forth, said piston having a tapered pin e on its front end adapted to fit the tapered bore of the nozzle and when in a forward position to project through the said bore and free the same from any sand which may have collected therein. The chamber C' receives the air-pressure from a pipe C², and when the 50 air is turned into this pipe it forces piston D backwardly and allows the air to blow into the body of the sander or the casting A to force the sand therefrom through pipe B, as before stated. A pipe E communicates with 55 the rear of the cylinder or chamber back of the piston D, and when air is turned into this pipe the piston will be forced forward and its taper pin will clean out the opening in the nozzle.

60 Fig. 3 represents the valve which is used to control the air-pressure to the pipes C² and E. The valve is indicated in its closed position, but when turned a quarter-way around in the direction of the arrow it is in its operative position—that is, so that the air-pressure will pass through the nozzle and force the sand into the pipe B—and upon giving the valve-handle a further quarter-turn it will be in the clean-out position—that is, to cause 65 the piston D to be forced forward for cleaning out. It will be understood that this valve will be placed in the cab within easy reach of the engineer or at any suitable point upon the car within reach of the motorman or attendant.

70 I claim as my invention—

75 In combination in a sander for cars, means for supplying the sand, a jet-nozzle, a chamber in rear of the same, a piston in the chamber having a clean-out pin, an air-supply pipe leading to the front of the chamber, an air-supply pipe leading to the rear of said chamber back of the piston and means for controlling said air-supplies, substantially as described.

80 In witness whereof I have hereunto set my hand in presence of two witnesses.

A. SHIELDS.
